Primary Examiner — Cynthia Ramirez

(74) Attorney, Agent, or Firm — McKee, Voorhees & Sease

(57) **CLAIM**

The ornamental design for a wheelbarrow cradle, as shown and described.

DESCRIPTION

FIG. 1 is a perspective view of the wheelbarrow cradle showing my new design;

FIG. 2 is a front view thereof;

FIG. 3 is a rear view thereof;

FIG. 4 is a side view thereof;

FIG. 5 is the other side view thereof; and,

FIG. 6 is a top view thereof.

The bottom of the wheelbarrow cradle is not part of the claimed design. The broken lines in the figures are to show environment and are not part of the claimed design.
